JEWELRY MAGNIFYING DISPLAY STAND

Alberta Kuhn and Frank J. Leikam, Russell, Kans.

Application August 10, 1954, Serial No. 31,802

Term of patent 14 years

(Cl. D80—9)

The single figure is a perspective view of a jewelry magnifying display stand showing our new design.

The appearance of the side of the article not shown is substantially the same as that shown in the single figure.

The broken lines are shown for illustrative purposes only.

We claim:

The ornamental design for a jewelry magnifying display stand, as shown and described.
